UNITED STATES PATENT OFFICE

ALBERT OLGAY, OF GLEN ELLYN, ILLINOIS, ASSIGNOR TO GAW-O'HARA ENVELOPE COMPANY, OF CHICAGO, ILLINOIS, A CORPORATION OF ILLINOIS

DIE

Application filed April 27, 1928. Serial No. 273,417.

This invention pertains to dies and more particularly to dies for gumming flaps of envelopes and the like. The dies described in this application are particularly useful in connection with envelope gumming and folding machines.

Many envelopes are made with triangular or substantially triangular bottom, side and closing flaps. The side flaps are ordinarily folded down against the inside surface of the face of the envelope and after gum has been applied along the free marginal edges of the bottom flap on the side that is to be folded against the side flap, it too is folded down and secured by the gum to the side flaps. The closing flap may or may not have gum applied along the free marginal edges of the side adapted to be folded against the side flaps, but if gum is applied to the closing flap it is ordinarily permitted to dry before the flap is folded down.

Heretofore gum has been applied to the marginal edges of the bottom flap or side flaps and to the marginal edges of the closing flap by hand or by flat straight face dies having a reciprocal motion which, when the envelope flap or portion of the flap to which the gum was to be applied, was moved relatively underneath the die and positioned thereunder, operated to apply the gum or mucilage. These prior methods of applying gum or mucilage to the flap require a great deal of labor and special machinery and have necessarily slowed production.

In accordance with the invention a die of such nature, character and shape is provided that the envelope or the like may have gum applied along marginal edges of the flaps along lines bearing any desired predetermined angular relation to the edge of the flap while the envelope blank is carried edgewise, that is, in the plane of the blank. The invention also contemplates the provision of a die which may be mounted on a rotating shaft adjacent a conveyor on which the envelope blanks are carried in edgewise relation so that gum or mucilage may be applied in the desired positions and along the envelope flap or flaps of each of a continuously moving succession of blanks. The invention

also contemplates the provision of gumming dies which may be arranged to apply gum along the marginal edges of triangular flaps of envelopes carried along in edgewise relation with a line joining the center of the base and the apex of the flap bearing substantially any predetermined angular relation to the line of travel of the envelope blanks. These may be said to be some of the objects of the invention.

Other objects include the provision of a die or dies of peculiar shape and arrangement as an article or articles of manufacture and a block or, rather, a cylinder composed of a plurality of pre-cut mating dies severally connected together for use and sale as an intermediate product of manufacture.

Many other objects as well as the advantages, uses and functions of the invention, which will be illustrated and described in a preferred form, will be, or should become, readily appreciated and understood after reading the following description and claims and after viewing the drawing, in which:

Fig. 1 is a plan view of a cylinder, the intermediate article of manufacture, showing a succession of mating male and female dies formed thereon and ready to be severed as and when desired for use.

Fig. 2 is an end elevational view of the cylinder shown in Fig. 1, and

Figs. 3, 4 and 5 are respectively end, side and top plan views of a female die severed from the cylinder and mounted on a bracket adapted to be secured to a rotating shaft of a combined gumming and folding machine.

The die illustrated in Figs. 3, 4 and 5, to which reference will first be made, comprises a base 2 and a pair of parallel ribs 3 projecting upwardly above the face 4 of the base so as to provide what may be termed impression or supporting surfaces 5 between which a groove or depression 6 extends from one end to the other of the die block. The die or die block, in the present instance, is suitably secured on a mounting block 7 as by screws 8, the top surface of the block 7 being suitably curved to conform to the bottom surface of the block 2. The mounting block 7 is provided with a stem 9 the lower end

of which is provided with an arcuate bracket arm 11 which mates with a cap 12 for clamping the assembly to a shaft or the like. Clamp screws 13 pass through suitable lugs 14 formed on the members 11 and 12 to draw them together.

The surfaces 5 extend helically and when developed provide a figure bounded on its longitudinal sides by straight parallel lines. 10 Thus, when the die face is rolled along a flat surface, the surfaces describe straight sided figures or substantially rectangular parallel areas therealong extending at an angle other than a straight angle to the line of rolling. When a single line of gum or mucilage is to be applied along the marginal edge of an envelope flap, the die illustrated in Figs. 3, 4 and 5 forms the supporting or female die and operates against the side of 15 the flap opposite that upon which the gum is applied, while the male die which has but one helical rib, adapted nicely to fit between the ribs 3 of the female die, carries the gum along its surface and rolling or rotating with the female die in indexed position thereto, applies the gum it carries to the opposite side of the paper. In practice the envelope blanks are carried along edgewise between the male and female gumming dies two pairs 20 of which may be arranged to gum both marginal edges of say, the bottom or closing flap of the envelope, while the dies mounted on a revolving shaft are rotated in timed relation to the travel of the blanks. Of course, 25 if the blanks be passed between the gumming dies with the triangular flap to be gummed, bearing such relation to the line of travel of the blanks that the marginal edges of the flap do not make equal angles 30 with the line of travel or the axis of the shaft upon which the gumming dies are mounted, it becomes necessary to provide dies the pitch of the gumming or impression 35 surfaces of which have a helical pitch corresponding to the angle which the marginal edge of the flap to be gummed make with the line of travel of the blank or the axis of the shaft upon which the dies are mounted. In 40 the present instance, the pitch angle of the dies is represented as 45°.

The dies may be simply made by following the following process and the resultant intermediate article of manufacture may be kept safely with the unused dies together and 45 in their proper relationships until another pair or pairs of dies may be required. In accordance with the invention a hollow cylinder or cylindrical sleeve of metal of which the dies are to be composed is mounted on its axis 50 between lathe centers for rotation. Any suitable cutting tool mounted for movement longitudinally of the cylinder axis is arranged adjacent the rotating cylinder and the cylinder is rotated and the tool moved at such relative rates of speed as will cause the tool to cut

the metal of the cylinder in a helical path and at such pitch angle as may be desired. Rather than cut two separate and independent cylinders to provide corresponding male and female dies of right and left hand pitch, I provide a cylinder of sufficient length, that corresponding and mating male and female dies may be cut from opposite end portions thereof with very little waste. In this way the time and labor of cutting the dies may be 70 much simplified, since if the cylinder shown in Fig. 1 be considered as rotating in a clockwise direction viewing the left-hand end thereof, two cutting tools each starting at an end of the cylinder and working toward the 75 middle thereof may be used and if necessary or desirable more than one tool may be used at the same time on each end for cutting a number of the dies in both ends simultaneously.

By cutting first a male and then a female die from each end of the cylinder with a left-hand male corresponding with a right-hand female and a left-hand female corresponding with a right-hand male (these pairs are mating dies), upper and lower, right and left-hand pairs of mating dies are provided and after the dies are cut an unskilled laborer, recognizing only the mating dies have their ends together in the cylinder, may cut them off, i. e., sever them from the other dies, and 85 use them. For the purpose of preserving the dies in their proper relationship until it is desired to use them, a portion of the cylinder between each male and female die at the same 90 end of the cylinder is cut away leaving a thin, 95 easily severable strip of metal 15 connecting them. Thus when it is desired to obtain a pair of mating left-hand or right-hand male and female dies, the desired male die is cut from one end portion and the desired female die is cut from the other end portion and 100 mounted on the supports for use as above described.

Owing to the impossibility of machining the left and right-hand dies right up to their 105 line of junction designated 16, there is a narrow portion on each side of the junction line 16, as for instance, between the lines 17—17, that must be cut off and wasted in so far as usefulness for the purposes of the other dies 110 are concerned. This, however, is a negligible amount of waste for substantially the whole cylinder is used for the dies.

It is believed that those skilled in the art 115 will thoroughly understand the invention from the foregoing description taken in connection with the drawing, but it should be understood that since various modifications and arrangements of the invention bearing little resemblance to the specific and preferred 120 form illustrated and described may be made, I do not desire to be limited by the preferred form illustrated and described, but only by the spirit of the invention and the scope of the 125 appended claims.

I claim:

1. As an article of manufacture, a hollow metal cylinder having a plurality of die impression surfaces formed in its surface adjacent one another and separated by a relatively thin severable strip of metal of the cylinder, each impression surface having a portion which is parallel a surface generated by a right line, lying wholly in the surface of a cylinder, which relatively moves uniformly about the axis of the cylinder, and at the same time relatively moves uniformly in a direction parallel said axis. 10
2. As an article of manufacture, a hollow cylinder having a plurality of helical die impression surfaces formed integrally in its surface adjacent one another and separated by a relatively thin severable strip of metal of the cylinder. 15
3. As an article of manufacture, a hollow cylinder having a plurality of die impression surfaces formed in its surface adjacent one another and separated by a relatively thin severable strip of metal of the cylinder, each 20 impression surface being of substantially greater length than breadth, one line of said surface extending longitudinally of but wholly in said surface being helical.
4. As an article of manufacture, a hollow cylinder having a plurality of die impression surfaces formed in its surface adjacent one another and separated by a relatively thin severable strip of metal of the cylinder, each impression surface being of substantially greater length than breadth, said surface being so shaped longitudinally and transversely as to receive a plurality of parallel, longitudinally extending, helical lines each wholly in said surface. 25
5. As an article of manufacture, a hollow metal cylinder having a plurality of die impression surfaces formed in its surface adjacent one another and separated by a relatively thin severable strip of metal of the cylinder, alternate impression surfaces each having a portion which is parallel a surface generated by a right line, lying wholly in the surface of a cylinder, which relatively moves uniformly about the axis of the cylinder, and at the same time relatively moves uniformly in a direction parallel said axis. 30
6. As an article of manufacture, a hollow cylinder having a plurality of die impression surfaces formed on its exterior adjacent one another and separated by relatively thin severable strips of metal of the cylinder, said surfaces and said strips being so relatively spaced as to provide when the strips are severed alternate dies each having a helical impression surface and intermediate dies having a pair of parallel, helically extending surfaces, every point in each of said surfaces being equi-distant from an axis of generation. 35
7. As an article of manufacture, a hollow metal cylinder having a plurality of die im-

pression surfaces formed on its exterior and a plurality of relatively thin severable strips of metal formed on the cylinder spaced relatively to said surfaces to provide between the severable strips severable alternate male and female right-handed helical dies adjacent one end of the cylinder and a plurality of alternate male and female left-handed helical dies adjacent the other end of the cylinder. 70

8. As an article of manufacture, a hollow metal cylinder having a plurality of die impression surfaces formed on its exterior and a plurality of relatively thin severable strips of metal of the cylinder spaced relatively to said surfaces to provide severable alternate male and female right-handed helical dies adjacent one end of the cylinder and a plurality of male and female left-handed helical dies adjacent the other end of the cylinder, the male die on one end being complementary to a female die on the other end of the cylinder. 75

In witness of the foregoing I affix my signature.
